(Cl. D80—9)

To all whom it may concern:

Be it known that I, Joseph C. Foster, a citizen of the United States, residing at Leominster, in the county of Worcester, State of Massachusetts, have invented a new, original, and ornamental Design for a Tie Tray or the like, of which the following is a specification, reference being had to the accompanying drawings, forming part thereof, in which:

Fig. 2 is a side view;

Fig. 3 is a bottom plan view;

Fig. 4 is a front view; and,

Fig. 5 is a rear view thereof.

I claim:

The ornamental design for a tie tray or the like, substantially as shown.

JOSEPH C. FOSTER.
